UNITED STATES PATENT OFFICE.

WARREN BREWER, OF NEW YORK, N. Y., ASSIGNOR TO THORNDIKE COMPANY, OF WEST WARREN, MASSACHUSETTS, A CORPORATION OF MASSACHUSETTS.

LOOM ATTACHMENT.

Application filed June 30, 1927. Serial No. 202,514.

This invention relates to improvements in looms, and has particular reference to an attachment therefor capable of producing ripples in mattress ticking.

5 An object of the invention is to utilize the operation of the lay of a loom to intermittently produce a slack in certain warp threads of a shed with which the weft threads are laid so that the finished fabric will be woven 10 with ripples therein.

Another object is to reciprocate a guide roller toward and away from certain warp threads to alternately place the same under tension and relieve said tension to produce a 15 slack in said threads at the shed of the loom whereby the weft threads are laid with the slackened threads to form ripples in the warp of the finished fabric.

The above and other objects will appear 20 more clearly from the following detail description, when taken in connection with the accompanying drawings, which illustrate a preferred embodiment of the inventive idea.

In the drawings—

25 Figure 1 is a fragmentary and partially diagrammatic view of a loom showing the improved attachment thereon in side elevation, with parts broken away and shown in section;

30 Figure 2 is a partially diagrammatic rear elevation; and

Figure 3 is a fragmentary plan view of a fabric made in accordance with the invention.

35 The invention is especially designed for making mattress ticking, but its application to the weaving of other fabrics is obvious. The attachment may be mounted on different types of looms with equal facility and, as 40 shown in the accompanying drawings, is applied to a loom comprising a frame generally indicated by the numeral 5 having the lower warp beam 6 journaled in the rear thereof from which warp threads 7 are fed to the weaving mechanism, the finished fabric 8 being thereupon wound upon the take-up roller 9. The frame 5 has the usual harness supported thereon including the heddles 10 which form the shed through which pass the 45 shuttles (not shown) operating in conjunction with the oscillatory lay 11 carrying the reed 12 that lays the weft threads against the warp threads to form the fabric 8.

In accordance with the present invention 50 it is preferable to guide the warp threads

from the beam 6 around the rollers 13 and 14 carried by the brackets 15 and over the roller 16 supported by the brackets 17, said brackets being attached to the rear of the frame 5. Other warp threads 18 are unwound from an upper or auxiliary beam 19 supported in standards 20 fixed to the frame 5 and these threads are guided through the heddles so as to combine with the threads 7 to form the warp of the fabric. 65

In connection with the threads 18 it is proposed to utilize a device on each side of the loom frame under the control of the lay 11 to alternately place said threads 18 under the usual tension to which the same are subjected 70 when being woven in the ordinary manner and then release said tension to permit the threads to slacken. This slackening of the threads extends to the shed formed by the heddles 10 and said threads are laid with the weft in their slackened condition with the result that ripples, indicated at 21 in the fabric 22 (Figure 3), are formed at intervals which impart to the fabric a unique appearance. 75

As shown in Figure 1, each of said devices on opposite sides of the frame 5 comprises a cylinder 23 pivotally supported at 24 intermediate its ends about an axis transverse thereto so as to permit of at least a limited 80 rocking movement of the cylinder if such is found necessary for the proper operation of the device. A rod 25 is extended through the cylinder 23 and is connected at its rear end to one end of the guide roller 26. This roller 90 is projected rearwardly under the influence of a spring 27 coiled in said cylinder and having one end engaged with the adjustable collar 28 on the rod 25 and its other end contacting the front end of the cylinder. In its rearward position the roller 26 engages the threads 18 and exerts sufficient pressure thereagainst to maintain them under tension. The rearward movement of the roller and consequently of the rod 25 may be limited by a collar 29 adjustable on said rod and engageable with the front end of the cylinder 23. When the roller 26 is moved forwardly against the tension of the spring 27, in the manner to presently appear, and assumes substantially the dotted line position shown in Figure 1, the tension on the threads 18 is released and they become slack and this slackness extends back to the shed where the weft threads are interwoven with the warp. 95 100 105 110

To accomplish the alternate tensioning and slackening of the threads 18, the oscillation of the lay 11 is used in conjunction with the spring 27. An abutment or contact member 30 is adjustably mounted on the rod 25 adjacent its front end and in the path of movement of the upper end of the lay. As the latter moves forwardly from its full line position to accomplish the laying of the weft with the warp by the reed 12, the upper end of the lay strikes the member 30 and, as a consequence, moves the rod 25 and roller 26 forwardly, the amount of such movement depending upon the position in which the member 30 is secured in its relation to the lay. The adjustability of the member 30 makes it possible to regulate the amount of slack to be obtained in the threads 18 with a corresponding change in distinctiveness of the ripples 21 in the finished fabric. As the lay starts its return or rearward movement, the spring 27, which has been compressed by the forward movement of said lay, now becomes effective to force the rod 25 and roller 26 rearwardly to again place the threads 18 under tension. This action is repeated as the weav-

ing progresses, resulting in the production of a fabric wherein certain warp threads are interwoven with the weft in a comparatively loose or slack condition to form rows or ripples with the ripples in each row spaced apart at fairly regular intervals. 30

What is claimed is:

In a loom, the combination with a frame, and a lay mounted therein; of a cylinder pivotally supported intermediate its ends by said frame, a rod extending through and slidable in said cylinder, a guide roller carried by one end of said rod and engaging certain of the warp threads to maintain them under tension, means carried by said rod on the opposite side of said cylinder from said roller and engaged by said lay to move said rod in one direction and thereby relieve the tension on said threads to produce a slack therein, and a spring in said cylinder to move said rod in the opposite direction to restore the tension on said warp threads subsequent to the laying of the weft threads therewith. 40

In testimony whereof I have affixed my 45 signature.

WARREN BREWER. 50
